CLOSURE LATCH

Stanley Duluk, Dearborn, and Wilson H. West, Madison Heights, Mich., assignors to General Motors Corporation, Detroit, Mich., a corporation of Delaware
Filed July 18, 1960, Ser. No. 43,666
4 Claims. (Cl. 292—113)

This invention relates to closure latches, and more particularly to a convertible top header latch assembly.

The primary object of this invention is to provide a new and improved convertible top header latch assembly which materially reduces the effort required of the operator to both latch and unlatch a top header to and from a windshield header. In accomplishing this object of the invention, the subject latch assembly includes a vertically swingable manually operable handle assembly which is movable between closed and open positions with respect to a latch housing on the top header, with the closed and open positions of the handle assembly corresponding respectively to the latched and unlatched positions of the latch assembly. By rotatably mounting the handle assembly on the top header for swinging movement about a generally horizontally disposed axis, the operator is permitted to use his leverage to the best advantage in order to move the handle between its terminal positions. The handle assembly is further selectively and alternately biased to either of its terminal positions, with locating means being provided to locate the handle assembly in both terminal positions against the biasing means. A latch bolt assembly is swingably mounted on the handle assembly and is biased toward latched position at all times. When the latch assembly is in latched position, the handle is in closed position and the latch bolt assembly is in latching engagement with the striker assembly on the windshield header, with the axis of swinging of the handle assembly on the housing being disposed to one side of a line through the axis of swinging of the latch bolt assembly on the handle assembly and the point of engagement of the latch bolt assembly with the striker assembly. When the handle assembly is moved to an open position, the handle biasing means initially resists movement of the handle assembly toward open position and thereafter aids such movement of the handle assembly. Since the latch bolt assembly is continually biased toward latched position, it will continuously engage the striker assembly and slide out of latching engagement therewith as the handle assembly moves toward open position, with the unlatched position of the latch bolt assembly being determined by interengaging means on the latch bolt assembly and on the handle assembly in the open position of the latter.

The operator can easily move the handle assembly between its open and closed positions despite the action of the biasing means which always initially resists movement of the handle assembly from one terminal position towards another terminal position for part of the movement thereof and thereafter aids movement of the handle assembly from the one terminal position to the other terminal position. By providing a handle assembly of this type and a latch bolt assembly which is rotatably mounted on the handle assembly and continually biased toward latched position, the operator need exert little effort in both latching and unlatching the top header to and from the windshield header, and further is permitted to use his leverage to the best possible advantage.

Other objects of this invention will be readily apparent from the following specification and drawings wherein:

FIGURE 1 is a partial perspective view of a convertible automobile having a convertible top mounted thereon and embodying a convertible top header latch assem-

2

bly according to this invention, with the latch assembly being shown in latched position;

FIGURE 2 is an enlarged partially broken away view of a portion of FIGURE 1;

FIGURE 3 is an enlarged sectional view taken generally along the plane indicated by line 3—3 of FIGURE 2; and

FIGURE 4 is a view similar to FIGURE 3 showing the latch assembly in an unlatched position.

10 Referring now to FIGURE 1 of the drawings a convertible vehicle 10 includes a windshield 12 which is housed within a windshield header 14. A convertible top frame 16 of known type is mounted on the body 10 for movement between a raised position, as shown, and a lowered position, not shown, with frame 16 supporting the usual convertible top fabric 18. Frame 16 includes a top header 20 which bears against the windshield header 14 in the raised position of the frame 16, with the top header 20 being latched to the windshield header 14 by a top header latch assembly 22 according to this invention. It will be understood that two such assemblies 22 are usually provided, one being located adjacent each end of the top header 20.

25 As shown in FIGURES 3 and 4 of the drawings, header 20 includes an upper member 24 and a lower member 26, with members 24 and 26 being secured together at 28 adjacent the forward edges thereof. A reinforcing member 30 interconnects the rear edge portions of members 24 and 26 adjacent the upper rearward edge of the top header 20. Members 26 and 30 are cut away to provide an opening 32 to receive the latch assembly 22.

30 Latch assembly 22 includes a housing 34 provided with a continuous peripheral flange 36 which is complementary to the shape of member 26 and is bolted thereto at 38.

35 A pair of spaced arcuately shaped ribs 40 of housing 36 define a longitudinally arcuate opening 42 therebetween. A generally arcuately shaped handle 44 fits within the opening 42 and includes a spaced pair of laterally extending arms 46 which are rotatably mounted on studs 48 fixed to the inner walls 50 of the ribs 40 in order to rotatably mount the handle 44 on the housing 34 for swinging movement between a closed position with respect thereto, as shown in FIGURE 3, and an open position with respect thereto, as shown in FIGURE 4. An over

40 center torsion spring 52 is located between each arm 46 and each wall 50, with each spring 52 having one end 54 thereof hooked within an opening in a wall 50 and the other end 56 thereof hooked within an opening in an arm 46. Springs 52 selectively and alternately bias the handle 44 to either its closed or to its open position. When the handle 44 is in a closed position as shown in FIGURE 3, springs 52 bias the arms 46 of the handle into engagement with a web 58 interconnecting the walls 50 of housing 34 in order to locate the handle 44 in this position.

45 When the handle 44 is moved from its closed position, as shown in FIGURE 3, to its open position, as shown in FIGURE 4, springs 52 will initially resist such movement of the handle 44 until the ends 56 of the spring come into alignment with the axes of studs 48 and the ends 54 of the spring. Thereafter, when the ends 56 of the springs pass beyond this aligned position, the springs 52 will then act to bias the handle to its open position, as shown in FIGURE 4, with the handle being located in this position by engagement of the finger piece 60 of the handle with a portion 62 of the flange 36 of housing 34.

50 A U-shaped bracket or latch bolt support member 64 is located between the arms 46 of the handle and is swingably mounted on the handle by pivot shaft 68 extending between the arms 46. The base of the bracket is provided with a threaded bore 70 which threadedly receives one end of a hook type latch bolt 72, with bolt 72 being adjustably secured to the bracket 64 by means of a set

screw 74. A coil torsion spring 76 surrounds shaft 68 intermediate the legs of the bracket 64, with one end 78 of the spring bearing against the inner surface of the handle 44 and the other end 80 of the spring bearing against one side of the base of bracket 64 in order to continually bias the latch bolt assembly, including the bolt 72 and the bracket 64, toward latched position or clockwise, as viewed in FIGURES 3 and 4 of the drawings, about the shaft 68.

When the handle 44 is in its closed position, as shown in FIGURE 3, bolt 72 will be in latching engagement with a lip 82 of a striker assembly 84 which is bolted at 86 to the windshield header 14. The striker assembly further includes a laterally extending apertured ear 88, FIGURES 1 and 2, which receives a conical headed guide pin 90 integral with the housing 34 in order to laterally locate the top header 26 with respect to the windshield header 14. The striker assembly 84 may also include a support 92 for a sun shade support arm 94 in order to mount a sun shade 96 on the windshiled header 14.

If it is desired to unlatch the latch assembly, the finger piece 60 is grasped by the operator and is moved rearwardly or upwardly in order to rotate the handle 44 counterclockwise about the studs 48 to open position. During such movement of the handle 44 to open position, springs 52 will initially act to resist the movement and thereafter aid the movement of handle 44, as previously described. During this movement of the handle, the latch bolt 72 will continuously slide downwardly and rearwardly relative to lip 82, as viewed in FIGURE 3, as the spring 76 continually biases the bracket 64 clockwise relative to the arms 46 as the arms 46 swing counterclockwise about the pivot studs 48. The bolt 72 continues to slide relative to the lip 82 of the striker assembly 84 as the handle 44 moves toward its open position. When the handle reaches its open position, the base of the bracket 64 will engage the lip 82, as shown in FIGURE 4, and the interengagement of shoulders 98 on the legs of the bracket 64 and a shoulder 100 on the handle 44 accurately locates the latch bolt assembly in this position prior to movement of the top to a lowered position.

The operator is aided in moving the handle 44 from its closed position to its open position by the seal pressure of the weatherstrip 102 which seals the convertible top header against the windshield header 14. Further, once the ends 56 of the springs 52 have moved into alignment with the axes of studs 48 and the ends 54 of the spring and then beyond such alignment, the springs 52 will then also aid the operator in moving the handle 44 from its closed position to its open position. Thus, very little effort is required of the operator in order to unlatch the top header from the windshield header.

If the top is thereafter moved from its lowered position to a raised position, the top header will be located with respect to the windshield header, as shown in FIGURE 4 of the drawings. The operator then grasps the finger piece 60 to move the handle 44 from its open position to its closed position. During this movement of the handle, the springs 52 will initially resist movement of the handle until the ends 56 thereof come into alignment with and pass beyond the line between the ends 54 of the springs and the axes of the studs 48. Thereafter the springs 52 will act to bias the handle 44 to its closed position and will aid the operator in compressing the weatherstrip 102 against the windshield header 14. During this movement of the handle 44, the spring 76 will continue to bias the bolt 72 toward latched position so that the bolt will slide upwardly ad forwardly of the lip 82 and into latching engagement therewith.

Thus this invention provides a new and improved convertible top header latch assembly.

What is claimed is:

1. Latch means for an automobile convertible top header movable into and out of engagement with a windshield header having striker means mounted thereon comprising, in combination, latch support means mounted on

said top header, latch operating means swingably mounted on said support means for movement between first and second terminal positions relative thereto corresponding to latched and unlatched positions of said latch means, 5 means selectively and alternately biasing said latch operating means to either of said terminal positions thereof, locating means engageable by said operating means in the terminal positions thereof under the action of said biasing means to locate said operating means in each of said positions, a latch bolt swingably mounted on said operating means for movement therewith and movement relative thereto, biasing means interconnecting said latch bolt and said operating means and continuously biasing said latch bolt to the latched position thereof, the pivotal 10 axis of said latch bolt and the point of engagement of said bolt with said striker means being located on opposite sides of the pivotal axis of said operating means on said support and over center with respect thereto in the latched position of said latch bolt whereby the over center relationship of said pivotal axes and said point of engagement of said operating means with said locating means holds said bolt in tight engagement with said striker means in the latched position thereof.

2. Latch means for an automobile convertible top 25 header movable into and out of engagement with a windshield header having striker means mounted thereon comprising, in combination, a support mounted on said top header, a latch operating member swingably mounted on said support for movement between first and second 30 terminal positions relative thereto corresponding to latched and unlatched positions of said latch means, first biasing means selectively and alternately biasing said latch operating member to either of said terminal positions thereof, locating means engageable by said operating member in the 35 terminal positions thereof under the action of said biasing means to locate said operating member in each of said positions, a latch bolt swingably mounted on said operating member for movement therewith and movement relative thereto, second biasing means interconnecting said 40 bolt and said operating member and continuously biasing said latch bolt to the latched position thereof, said second biasing means biasing said bolt into engagement with said striker means in said first terminal position of said operating member, and means on said operating member engageable by said bolt in the unlatched position thereof and 45 second position of said operating member to locate said bolt in said unlatched position with respect to said striker means.

3. Latch means for an automobile convertible top 50 header movable into and out of engagement with a windshield header having striker means mounted thereon comprising, in combination, a latch support mounted on said top header, a latch operating member swingably mounted on said support for movement between first and 55 second terminal positions relative thereto corresponding to latched and unlatched positions of said latch means, first biasing means selectively and alternately biasing said operating member to either of said terminal positions thereof, locating means engageable by said operating member in the terminal positions thereof to locate said member in each of said positions, a latch bolt swingably mounted on said operating member for movement therewith and movement relative thereto between latched and unlatched positions, second biasing means interconnecting 60 said bolt and said operating member and continuously biasing said bolt to the latched position thereof, the pivotal axis of said bolt and the point of engagement of said bolt with said striker means being located to either side of the pivotal axis of said operating member on said support and over center with respect thereto in the latched position of said bolt and first position of said member to hold said bolt in tight engagement with said striker means, movement of said member to said second position thereof causing said pivotal axis of said bolt to move over center 65 with respect to said axis of said operating member and

said point of engagement to permit said second biasing means to cause said bolt to slide relative to said striker means and out of engagement therewith.

4. Latch means for an automobile convertible top header movable into and out of engagement with a windshield header having striker means mounted thereon comprising, in combination, a latch support mounted on said top header, a latch operating member swingably mounted on said support for movement between first and second terminal positions relative thereto corresponding to latched and unlatched positions of said latch means, means selectively and alternately biasing said latch operating member to either of said terminal positions thereof, a latch bolt swingably mounted on said operating member for movement therewith and movement relative thereto, second biasing means interconnecting said latch bolt and said operating member and continuously biasing said latch bolt to the latched position thereof, the pivotal axis of said latch bolt being located to one side of a line through the point of engagement of said bolt with said striker means and the pivotal axis of said operating member on said support in the latched position of said latch bolt and first terminal position of said operating member, move-

ment of said operating member from said first terminal position thereof to said second terminal position thereof moving the pivotal axis of said latch bolt to the other side of said line to permit said second biasing means to move said bolt relative to said striker means, and means on said operating member engageable by means on said bolt to limit movement of said bolt relative to said striker means by said second biasing means and to locate said bolt in the unlatched position thereof and second terminal position of said operating member.
